STOKER MECHANISM

Howard P. Anderson, Erie, Pa., assignor to The Standard Stoker Company, Incorporated, a corporation of Delaware

**Application December 29, 1933, Serial No. 704,412
Renewed November 19, 1935**

19 Claims. (Cl. 122—4)

This invention relates to improvements in locomotive stokers of the type that feed through the lower portion of the firing opening in the boiler backhead.

5 In stokers of this type it has been customary
to provide the forward end of the discharge cas-
ing with laterally extending flanges, through
which flanges the casing is attached to the boiler
backhead by suitable fastening means, as by
10 bolts. Since the slope of the backhead of the
different types of locomotives varies, it is obvious
that in prior installations a particular form of
discharge casing had to be provided for each
15 different style backhead. The present invention
obviates the necessity of providing a number of
different forms of discharge casing, permitting
the use of a standard discharge casing regardless
of the slope of the firebox backwall by providing
20 a novel frame member arranged to be secured
to the backhead and arranged to receive a stand-
ard discharge casing. This frame member is a
relatively simple casting compared to the dis-
charge casing, therefore the frame member is
25 made to suit the slope of the backhead permit-
ting the use of a standard discharge casing.

25 The novel frame member is made to embrace the entire firing opening and while the lower portion is arranged for attachment with the discharge casing, the upper portion is arranged to 30 receive and forms a support for a firedoor.

The invention further contemplates the provision of a frame member, having an annular plate like portion rigidly secured to the outer sheet of the firebox backwall and an annular convex flange at its free end attached to the inner sheet of the firebox backwall, the convex flange portion forming the walls of the firebox firing opening.

Other objects and advantages of the invention
40 reside in the features of construction, the combination of elements and arrangement of parts hereinafter more fully described and claimed and illustrated in the accompanying drawings, in which

45 Fig. 1 is a central longitudinal vertical section of a portion of a locomotive with a stoker therefor showing the invention in place;

Fig. 2 is a view in elevation of the novel frame member;

Fig. 4 is a view similar to the view shown in Fig. 1 of a modified form of the invention; and

Fig. 5 is a view in elevation of the novel frame member of the modified form of the invention.

In the drawings, the locomotive is indicated generally by the numeral 10 and is provided with a deck 11 and a firebox backwall 12 having a firing opening 13 therein. Fuel is delivered to the firing opening 13 from a tender, not shown, by stoker mechanism, only so much of which is shown that is essential to a complete understanding of the invention. The part of the stoking device illustrated comprises a discharge casing 14 which, as is well understood, is at the forward end of a series of conduit elements leading from the tender. 5 10

An annular member 15 overlaps and is secured to the outside of the outer sheet 16 of the back-head 12 by suitable means, as by staybolts 17. An annular convex flange 18 is formed with and extends inwardly from the inner marginal edge of the annular member 15 and is secured at its free end to the inside of the inner sheet 19 of the backhead 12 by suitable means, as by staybolts 20. The convex flange 18 forms a wall joining the inner and outer sheets of the back-head and defines the firing opening 13. A flange 40 extends outwardly from the inner marginal edge of the upper half of the annular member 15.

A pair of spaced hollow flange members 21 are formed with the lower half of the annular member 15 and extend outwardly therefrom adjacent the inner marginal edge thereof. The outer surfaces 22 of the flanges 21 are disposed angularly with respect to the surface of the annular member 15. The angularity of the flanges 21 will depend upon the type and slope of the firebox backwall of the locomotive in which the stoker is being installed. By changing the angularity of the flanges 21 to suit the particular backhead, the stoker discharge casing 14 may be of standard form, the one form of casing will then be suitable for any installation. The inner side faces of the flanges 21 are shaped to conform with the contour of the open forward end of the discharge casing 14.

The discharge casing 14 at its discharge end is provided with the laterally extending flanges 23 that rest flush against the surface 22 of the flanges 21. Bosses 24 are formed on the annular member 15 within the hollow flanges 21 and are provided with threaded openings 25. The discharge casing is rigidly secured to the annular member 15 by bolts 26 passing through the flanges 23 and threaded in the threaded openings 25. A fuel distributing plate 27 extends forwardly from the lower wall of the discharge end of the casing 14 through the lower portion of the space between the flanges 21 and through the firing 55

opening 13. Fuel is delivered onto the distributing plate 21 from the discharge casing 14 and is projected thereover by blasts of fluid under pressure issuing from a distributor jet member 28 located at the rear of the plate 21.

The upper portion of the annular member 15 is arranged to carry a firedoor for the opening defined by the marginal edges of the free end of the flange 40 and the upper forward end of the discharge casing 14. The annular member 15 is provided with the trunnions 29 from which is supported the firedoor 31. The firedoor may be of any suitable conventional type and the operating mechanism therefor may be of suitable conventional type, that shown in the drawings being of the well known "Franklin Butterfly" type.

Figures 4 and 5 show a modified form of the invention, in which, the frame or plate member 32 comprises top and side portions surrounding corresponding portions of the firing opening 33. However, it will be obvious that the frame member 32 may be made to entirely surround the firing opening if desired, in the manner that the annular plate 15 of the preferred form of the invention does. The frame member 32 is provided with laterally projecting lugs 34 arranged to receive bolts or studs 35 for attaching the frame member 32 rigidly to the firebox backhead 36. Unlike the preferred form of the invention, the frame member is not provided with an annular convex flange forming the walls of the firing opening, but the firing openings walls are formed by the inner and outer sheets 37 and 38, respectively, of the backhead 36, that are curved inwardly toward each other. In all other structural and functional respects the modified form of the invention is similar to the preferred form of the invention.

I claim:

- 40 1. As an article of manufacture, a frame for a firing opening comprising an annular plate like member, a pair of walled hollow flanges extending outwardly from the surface of said annular plate adjacent its inner marginal edge and spaced apart a distance sufficient to receive a fuel feed casing, the face of said flanges constituting the free end thereof being angularly disposed with respect to the surface of said annular plate like member.
- 50 2. As an article of manufacture, a frame for a firing opening comprising a curvate plate like member, a curved flange extending outwardly from a portion of the inner marginal edge of said curvate member, and a walled hollow flange extending outwardly from said curvate member adjacent each of the extremities of said curved flange, said walled hollow flanges being spaced apart a distance sufficient to receive a fuel feed casing.
- 60 3. As an article of manufacture, a frame for a firing opening comprising a curvate plate like member, a curved flange extending outwardly from a portion of the inner marginal edge of said curvate member and a walled hollow flange extending outwardly from said curvate member adjacent each of the extremities of said curved flange, said walled hollow flanges being spaced apart a distance sufficient to receive a fuel feed casing.
- 70 4. As an article of manufacture, a frame for a firing opening comprising a curvate plate like member, a curved flange extending outwardly from

from a portion of the inner marginal edge of said curvate member, a walled hollow flange extending outwardly from said curvate member adjacent each of the extremities of said curved flange, said walled hollow flanges being spaced apart a distance sufficient to receive a fuel feed casing and a pair of trunnions extending outwardly from said curvate member intermediate the extremities of said curved flange. 5

5. As an article of manufacture, a frame for a 10 firing opening comprising an annular plate like member, a pair of walled hollow flanges extending outwardly from the surface of said annular plate adjacent its inner marginal edge and spaced apart a distance sufficient to receive a fuel feed 15 casing, the face of said flanges constituting the free end thereof being angularly disposed with respect to the surface of said annular plate like member and bosses having threaded openings therein formed with and extending outwardly 20 from said annular member within said walled hollow flanges.

6. As an article of manufacture, a frame for a firing opening comprising an annular plate like member, a curved flange extending outwardly 25 from one face of said annular member along a portion of the inner marginal edge of said annular member, a walled hollow flange extending outwardly from said annular member adjacent each of the extremities of said curved flange, said 30 walled hollow flanges being spaced apart a distance sufficient to receive a fuel feed casing and an annular convex flange extending outwardly from the other face of said annular member along its inner marginal edge. 35

7. As an article of manufacture, a frame for a firing opening comprising an annular plate like member, a curved flange extending outwardly 40 from one face of said annular member along a portion of the inner marginal edge of said annular member, a walled hollow flange extending outwardly from said annular member adjacent each of the extremities of said curved flange, said 45 walled hollow flanges being spaced apart a distance sufficient to receive a fuel feed casing, the face of said last named flanges constituting the free end thereof being angularly disposed with respect to the surface of said annular plate like member and an annular convex flange extending outwardly from the other face of said annular 50 member along its inner marginal edge.

8. In combination with a firebox having a back-wall with a firing opening therein, a curvate plate like member rigidly secured to said back-wall in approximate register with said firing opening, spaced flanges extending outwardly from the lower half of the curvate member, a stoker discharge casing communicating with the lower half of the opening in said curvate member, said discharge casing having laterally extending 60 flanges at its forward end abutting the flanges on said curvate member and means extending through said flanges for rigidly securing said casing to said curvate member. 55

9. In combination with a firebox having a back-wall with a firing opening therein, a stoker comprising a discharge casing communicating with said firing opening, said casing having flanges extending laterally therefrom adjacent its discharge end, a curvate plate like member rigidly secured 70 to the firebox backwall in approximate register with said firing opening, said curvate member carrying on its lower half spaced flanges extending outwardly therefrom and arranged to abut the flanges on said casing, means for rigidly se- 75

curing said flanges together, the upper half of said curvate member carrying on its inner marginal edge an outwardly extending flange, and a door secured from said curvate member and arranged 5 to form a closure for the opening described by the outer edge of said last named flange and the upper forward edge of the said discharge casing.

10. In combination with a firebox having a backwall with a firing opening therein, an annular plate like member rigidly secured to said backwall in approximate register with said firing opening, a pair of spaced flanges extending outwardly from said annular member adjacent the lower inner marginal edge thereof, the surface of 15 said flanges at their outer ends being angularly disposed with respect to the surface of said annular member, a stoker discharge casing communicating with the lower half of the opening in said annular member, said discharge casing having laterally extending flanges at its forward end abutting said spaced flanges, means extending through said abutting flanges for rigidly securing 20 said casing to said annular member and a fire-door carried by the annular member and arranged 25 to form a closure for the upper half of the opening in said annular member.

11. In combination with a firebox having a backwall with a firing opening therein, an annular plate like member rigidly secured to said backwall in approximate register with said firing opening, a pair of spaced flanges extending outwardly from said annular member adjacent the lower inner marginal edge thereof, the surface of 30 said flanges at their outer ends being angularly disposed with respect to the surface of said annular member, a stoker discharge casing communicating with the lower half of the opening in said annular member, said discharge casing having laterally extending flanges at its forward end abutting said spaced flanges, means extending through 35 said abutting flanges for rigidly securing said casing to said annular member, a flange extending outwardly from the inner marginal edge of the upper portion of the opening in said annular member, and a firedoor secured from said annular member and arranged to form a closure for the opening described by the outer edge of said last named flange and the upper forward edge of the discharge casing.

50 12. In combination with a firebox having a backwall including an inner and an outer sheet with a firing opening therethrough, an annular plate like member rigidly secured to the outer sheet of said backwall in approximate register 55 with said firing opening, an annular convex flange formed with said annular member and extending outwardly from the inner marginal edge of the opening therein, said flange at its free end being rigidly secured to the inner sheet of said backwall 60 and forming the walls of said firing opening, spaced flanges extending outwardly from the lower half of the annular member in the opposite direction from said annular convex flange, a stoker discharge casing communicating with the 65 lower half of the opening in said annular member, said discharge casing having laterally extending flanges at its forward end butting said spaced flanges, means extending through said spaced flanges and said casing flanges for rigidly securing 70 said casing to said annular member and a firedoor carried by the annular member and arranged to form a closure for the upper half of the opening in said annular member.

13. In combination with a firebox having a backwall including an inner and an outer sheet with

a firing opening therethrough, an annular plate like member rigidly secured to the outer sheet of said backwall in approximate register with said firing opening, an annular convex flange formed with said annular member and extending outwardly from the inner marginal edge of the opening therein, said flange at its free end being rigidly secured to the inner sheet of said backwall and forming the walls of said firing opening, spaced flanges extending outwardly from the lower half of the annular member in the opposite direction from said annular convex flange, a stoker discharge casing communicating with the lower half of the opening in said annular member, said discharge casing having laterally extending flanges at its forward end abutting said spaced flanges, means extending through said spaced flanges and said casing flanges for rigidly securing said casing to said annular member, a curved flange extending outwardly in the same direction as said spaced flanges from the inner marginal edge of the upper half of the annular member and a firedoor secured from said annular member and arranged to form a closure for the opening described by the outer edge of said curved flange and the upper forward edge of said discharge casing.

14. In combination with a firebox having a backwall including an inner and an outer sheet with a firing opening therethrough, an annular plate 30 like member rigidly secured to the outer sheet of said backwall in approximate register with said firing opening, an annular convex flange formed with said annular member and extending outwardly from the inner marginal edge of the opening therein, said flange at its free end being rigidly secured to the inner sheet of said backwall and forming the walls of said firing opening, spaced flanges extending outwardly from the lower half of the annular member in the opposite direction 35 from said annular convex flange, the outer faces of said spaced flanges being angularly disposed with respect to the surface of said annular member, a stoker discharge casing communicating with the lower half of the opening in said annular member, said discharge casing having laterally extending flanges at its forward end abutting said spaced flanges, means extending through 40 said spaced flanges and said casing flanges for rigidly securing said casing to said annular member and a firedoor secured from said annular member and arranged to form a closure for the upper half of the opening in said annular member.

50 15. As an article of manufacture, a frame for a firing opening comprising a curvate plate-like member, a curved flange extending outwardly from the face of said member adjacent a portion of its inner marginal edge, a flange at each end of said curved flange extending outwardly from the face of said curvate member, the plane 55 of the free edges of said last named flanges being angularly disposed with respect to the plane of the face of said curvate member.

65 16. As an article of manufacture, a frame for a firing opening comprising a curvate plate-like member, flanged members extending outwardly from the face of said curvate member and spaced apart a distance sufficient to receive a fuel feed casing, the plane of the free edges of said flanged members being angularly disposed with respect 70 to the plane of the face of said curvate member.

17. As an article of manufacture, a frame for a firing opening comprising an annular plate-like member, a curved flange extending outwardly from one face of said member adjacent a portion 75

of its inner marginal edge, a flange at each end of said curved flange extending outwardly from the same face of said member, and an annular convex flange extending outwardly from the other face of said annular member adjacent its inner marginal edge.

18. As an article of manufacture, a frame for a firing opening comprising an annular plate-like member, a curved flange extending outwardly from one face of said member adjacent a portion of its inner marginal edge, a flange at each end of said curved flange extending outwardly from the same face of said member, the plane of the free edges of said last named flanges being angularly disposed with respect to the plane of the face of said annular member, and an annular convex flange extending outwardly from the other face of said annular member adjacent its inner marginal edge.

19. In combination with a firebox having a back-wall with a firing opening therein, a stoker comprising a discharge casing communicating with said firing opening, a curvate plate-like member rigidly secured to said backwall in approximate register with the firing opening, a curved flange extending outwardly from the face of the upper portion of said curvate member, flanged members extending outwardly from the face of the lower portion of said curvate member and spaced apart a distance sufficient to receive said discharge casing, and a door secured from said curvate member and arranged to form a closure for the opening described by the outer edge of said first named flange and the upper forward edge of the discharge casing.

HOWARD P. ANDERSON.
